O. W. GRUNDMANN,
SWIMMING DEVICE,
APPLICATION FILED AUG. 1, 1921.

1,395,914.

Patented Nov. 1, 1921.

Inventor
Otto William Grundmann

By his Attorney
Max F. Orduna, Jr.

UNITED STATES PATENT OFFICE.

OTTO WILLIAM GRUNDMANN, OF JERSEY CITY, NEW JERSEY.

SWIMMING DEVICE.

1,895,914.

Specification of Letters Patent. Patented Nov. 1, 1921.

Application filed August 1, 1921. Serial No. 488,898.

To all whom it may concern:

Be it known that I, OTTO WILLIAM GRUNDMANN, a citizen of the United States of America, and a resident of Jersey City, county of Hudson, State of New Jersey, have invented certain new and useful Improvements in Swimming Devices, of which the following is a specification.

The present invention relates to swimming devices for the attachment to the hands of a swimmer, and has for its object to provide an improved construction whereby the bearing surface of the hand will be enlarged without interfering with the wrist movements.

Another object of this invention is to produce a swimming device which when attached to the hand will be prevented from shifting in any direction, yet permit the bending of the fingers during the overhead stroke.

With these and other objects in view my invention consists in the novel construction, combination and arrangement of parts as will be hereinafter more fully described and defined in the appended claims.

In the accompanying drawing

Figures 1 to 4 show plan views of different modifications of a swimming device or plate, and Figs. 5, 6, 7 and 8 are sections on lines 5-5; 6-6; 7-7; and 8-8 respectively.

Referring specifically to the drawing the swimming device consists of a pair of plates of rigid material, preferably aluminum, one for each hand, each shaped to conform in outline with the natural shape of a hand, but somewhat larger in area so as to present a greater bearing surface to the water and thereby assist in propulsion of the swimmer. These plates may be made of a single piece, as plates 10 shown in Figs. 1 and 2 or may be composed of two pivotally connected sections as plates 10' 10" shown in Figs. 3 and 4. The edge of the plate surrounding the finger tips may be curved to form a centrally pointed part 10" whereby the strokes can be carried out with little resistance. The device may be attached to extend over the outer face or the palm of the hand. Two separate attachment means are used, one to encircle the fingers and the other the palm of the hand.

According to the construction shown in Fig. 1 the attachment over the fingers consists of straps 11, 11', permanently attached

in any suitable manner to the plate at 11^a and the free ends of which are adapted to be tightened together by a suitable buckle b. The attachment over the palm of the hand comprises a strap 12 permanently fixed to the plate at 12^a and passed in a twisted position through a slot 13' of a member 13 made of metal or the like. This member is attached to a short strap 14 passing through a second slot 13^a thereof and carrying a buckle b serving to tighten a third strap 16 fixed to the plate at 16'.

In the modification shown in Fig. 2, a single wrist or thumb strap 17 carrying a buckle b is used. This strap is passed through slots 19 in the plate in the manner shown.

To facilitate overhead stroke swimming requiring the bending of the hand, the plate may be constructed as follows:

The plate 10' is divided transversely along the knuckle part of the hand into two parts pivotally connected together by hinges 21, 21' or the like fixed to the inner face of the plate. This plate may be attached to the hand by similar straps to those shown in Figs. 1 and 2 or the following construction may be used. A single finger strap 22 is used passing around the plate through slots 23 of the latter, and is to be tightened by a buckle b. The wrist or thumb attachment is composed of straps 25, 26 fixed at 25' and 26' to the plate. The strap 26 is passed through slots 27, to have its free end tightened by the buckle b.

In this modification the adjoining edges of the two sections bear on each other. The sections may be locked in unfolded position to form a rigid piece by a locking bolt 29 as shown in Figs. 3 and 6.

In Fig. 4 the plate 10" is also composed of two transversely divided and hinged parts, but the latter are cut out at their adjoining edges to form a concavo-convex opening 31 which may be suitably covered by a piece of canvas 32 or other flexible material to prevent friction or injury to the knuckles of the hand when swinging the sections during the overhead stroke. The finger straps here shown are similar to those shown in Figs. 1 and 2. The thumb or wrist attachment consists of a single strap 33, as in Fig. 2 which is passed through slots 34 in the plate and through a loop 35 projecting from the plate near the thumb portion thereof. (Figs. 4 and 7.)

It will be seen that by my novel construction the greatest resistance offered by the water will be presented on the most effective part of the hand. By virtue of the shape given to the plates the same will not interfere with the movement of the wrists.

The edges of the plate may be properly rounded to prevent injury when handling the same.

10 What I claim and desire to secure by Letters Patent is:—

1. In a swimming device, a plate of rigid material shaped to conform with the natural outline of a hand and divided transversely 15 near the knuckle part into two sections pivoted to one another, the adjoining edges of said plate being cut out to leave a free space around the knuckles, a piece of flexible material covering said space and means for the 20 attachment of said device to the hand.

2. In a swimming device, a plate of rigid

material, divided transversely into sections pivotally connected together, a lock for locking said sections in outstretched position and means for the attachment of the 25 device to the hand.

3. In a swimming device, a plate of rigid material, and attachment means including two straps of which one is permanently fixed at both ends to said plate in a twisted position and the other is fixed to said plate at one end, a member carried by said twisted strap and adapted to be engaged by the free end of said second strap and means for tightening said second strap. 30

Signed at New York, this 30 day of July 35
1921.

OTTO WILLIAM GRUNDMANN.
